UNITED STATES PATENT OFFICE.

PHILIP A. LEACH, OF EAST BRIMFIELD, MASSACHUSETTS.

FORGE CLAMP.

1,423,123.

Specification of Letters Patent.

Patented July 18, 1922.

Application filed January 31, 1921. Serial No. 441,283.

To all whom it may concern:

Be it known that I, PHILIP A. LEACH, a citizen of the United States, residing at East Brimfield, in the county of Hampden 5 and State of Massachusetts, have invented a new and useful Forge Clamp, of which the following is a specification.

This invention relates to a clamp which I have found particularly valuable for use in 10 the fastening of the top arch of a forge, but although I have designed it especially for that use, it is capable of general use and is adapted for clamping cement forms and various other structures.

15 The principal object of the invention is to provide a construction of clamp consisting of a pair of castings or forgings and means for holding them together, with an efficient and simple means for exerting pressure between the two members in such a way 20 that the clamping jaws will be forced toward each other at a distance from the top of the clamp with any desired degree of pressure; and also to provide these parts in 25 such form that they can be made with very little machining or other expensive work.

Reference is to be had to the accompanying drawings in which—

Fig. 1 is a front elevation of a forge or 30 heating furnace showing a plurality of clamps applied thereto and embodying the features of this invention, and

Fig. 2 is an end view of the same.

The arch of this furnace or forge is shown 35 as formed of a plurality of fire bricks 10 set up edgewise and having a horizontal surface for the top. This surface is shown as covered by a metal plate 11 which does not constitute a part of the clamp. The 40 front of the furnace is also shown as closed by two fire bricks 12 set up end to end flatwise.

I employ the clamp which is the subject 45 of this invention to clamp and hold the two front bricks 12 as well as two courses of arch bricks 10. It will be understood that these bricks 10 and 12 are located on the top of the forge or furnace which has an opening 13 in the front through which the 50 pieces of metal to be heated are inserted and withdrawn. I have shown two of the clamps at the top and one of them at the front. As they are all constructed in the same way I will describe only one of them 55 in detail.

The clamp consists of two castings or

forgings 20 both exactly alike as they are originally constructed. Each of them is provided with a horizontal body 21 and with a vertical jaw 22 at the end of the same, 60 and substantially at right angles to it preferably. This jaw is a right angle projection on the end of the body and opposite it is a projection 23 which is perforated to provide a bolt hole. This preferably is connected with the main body 21 by a web 24 for strengthening purposes. In the same way the opposite end of the clamp member is provided in the form of an arm 25. This is located substantially at right angles to 70 the main body 21 and parallel to the jaw 22. Its point of connection with the body is strengthened and it extends up a material distance above the flat main body 21.

In the manufacture of the clamp two of 75 these members are formed and placed together with their arms 25 adjacent to each other and their jaws 22 located at opposite ends of the structure. The two projections 23 and the two arms 25 are provided with 80 bolt holes in alignment with each other and a bolt 26 is passed through them parallel with the main body 21. Its nuts are screwed up to bring the upper ends of the jaws substantially in contact with the bricks 85 or other elements which it is designed to clamp.

The two arms 25, although described as parallel with each other, preferably are made to diverge slightly by placing them 90 at a slight angle to the vertical. Through one of them is tapped a hole for a pressure screw 27 and the other one may be provided with a depression for receiving the end of it if desired. This is the only 95 difference in the construction of the two halves of the clamp.

After the clamp is set up in the manner above indicated the screw 27 is screwed up as tight as may be necessary in order to 100 force the lower ends of the jaws 22 toward each other with sufficient pressure to firmly grip the bricks or other structure to which the clamp is to be applied. This constitutes an easily operated clamp of simple 105 construction, consisting of few parts, and involving very little expensive machine work. It provides an efficient leverage for the purpose intended and exerts the pressure at a distance from the top of the article which is being held.

It is to be noted that the bolt 26 not only

constitutes means for holding the two members of the clamp together but the nuts, or head and nut, on its ends serve to prevent the jaws from moving about at the top, and in fact constitute in effect pivots on which these jaws can be caused to swing by the pressure exerted by the screw 27. In this way the bolt 26 serves two purposes effectively.

10 When used for a forge or annealing or hardening furnace the clamp will remain permanently in position as long as the bricks last, and it is of such structure that it is not easily injured by the heat of the 15 furnace. It can be set up in position very quickly and disconnected with equal rapidity.

Although I have illustrated and described only one form of the invention I am aware 20 of the fact that modifications can be made therein by any one skilled in the art and that the invention can be used for clamping purposes in general without departing

from the scope of the invention as expressed in the claim.

25

Therefore I do not wish to be limited to all the details of construction herein shown and described, or to the particular use illustrated, but what I do claim is:—

In a clamp, the combination of a pair 30 of members each having a horizontal main portion and two arms or projections extending upwardly therefrom at opposite ends, and a jaw extending downwardly therefrom in alignment with one of said 35 projections, means extending through the two pairs of arms and projections just above the horizontal position for pivotally connecting them together at that point, and means mounted on one of the arms for engaging the corresponding arm on the other member and forcing them apart at their extreme ends.

In testimony whereof I have hereunto affixed my signature.

PHILIP A. LEACH.
